PRINTING PRESS

Curtis S. Crafts, Oak Park, Ill., assignor to The
Goss Printing Press Company, Chicago, Ill., a
corporation of Illinois

Application May 19, 1936, Serial No. 80,484
Renewed July 1, 1939

13 Claims. (Cl. 101—157)

The invention relates to new and useful improvements in inking mechanisms for printing presses, and more especially to such improvements in inking mechanisms constituting a part of rotary intaglio presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is an elevation, with parts in section and parts broken away, of a press embodying the invention; and

Fig. 2 is a plan view on line 2—2 of Fig. 1, with the splash plate broken away.

Objects of the invention are to provide a novel intaglio inking mechanism of great efficiency and of simple construction and easy adjustment and operation, and to provide the same especially well capacitated to employ quick-drying inks in high-speed presses; to provide a novel inking system preferably combining the advantages of regulated immersive inking of the rotating design concurrent with the impactive action of a sheet of ink against the design, while at the same time maintaining regulable circulative flow of the entire ink body, together with continuous cleansing of the ink stream; to provide simple and immediate regulation of the depth of immersion of the design cylinder in the ink body, the total quantity of the ink flow, and the combined immersive and impactive inking action upon the rotating design; to provide for cleansing the design by the impactive ink stream, and especially to secure such action on the freshly inked design, and applied preferably contrary to the direction of rotation of the design; to secure powerful and adequate inking for fast intaglio printing, while at the same time exposing only a relatively small proportion of the ink outside the circulating system and thereby reducing evaporative action to a minimum consistent with the maintenance of the foregoingly described inking action and conditions.

Referring now in detail to the accompanying drawings, illustrating by way of example one embodiment of the invention, an intaglio design cylinder 1 is journaled in the side frames 2 of the press and an impression cylinder 3 is journaled in the press frame and cooperates with the cylinder 1 to print the web. A backing cylinder 4 for the impression cylinder 3 is likewise journaled in the press frame. The foregoing mechanism may be of any known or suitable form 10 for effecting intaglio printing in so far as regards the main novel features of the present invention.

In accordance with the present invention inking means for the design cylinder are provided 15 comprising a reservoir or body of ink in which the design cylinder continuously runs, and also a sheet-like stream of ink projected against the intaglio design as the cylinder rotates in the body of ink, and in accordance with one feature of the invention, the sheet-like stream is projected against the inked design and in the opposite direction to the rotation of the design cylinder. As embodied, a parti-cylindrical ink trough 12 is mounted to maintain the body of 25 ink in which the design cylinder is partly immersed as it rotates, and in accordance with one feature of the invention, means are provided for varying the depth of immersion of the design cylinder in the ink. In said embodied form the 30 ink trough 12 has two flat ends 13 and 14, and has a horizontally-disposed pivotal mounting 16 along one of its side edges, and in the present embodiment the ink supply pipe is used as the 35 pivotal support as will be later more fully described. The opposite side edge 15 of the trough 12 is used as a spillway edge for the ink in the trough, the level of this spillage edge being varied to vary the depth of immersion of the design cylinder in the ink contained in the trough. 40 Said level changing means, as embodied, comprises a plurality of pins 20, 21 and 22 mounted at either end of the ink trough 12 and projecting outwardly therefrom. Mounted on either side frame 2 of the press is an arm 24 pivotally mounted on a pin 25, which is fixed to the press side frame and projects inwardly therefrom. Each of the arms 24 has at its bottom end a notch or hook 26 into which any one of the pins 20, 21 or 22 on that side of the trough is adapted 45 to enter and to be supported by the arm. Each arm 24 has a handle 27. By reason of the hook engaging any one of the pins, the angular position of the trough 12 about its pivotal support 16 is changed and thereby the level of the spill- 50 55

age edge 15 and the depth of immersion of the design cylinder in the body of the ink in the trough is regulated and varied.

In the present embodiment of the invention, 5 a circulating ink system is provided and in connection therewith means for projecting the sheet-like stream of ink against the design cylinder. In said embodied means an ink supply pipe 31 has a horizontal reach supported in the 10 side frames of the press, and this pipe conveniently constitutes the pivotal mounting for the ink trough 12 as already described. The horizontal reach of the supply pipe 31 extends along and is contiguous to the design cylinder, 15 and has an ink ejecting slot or plurality of ejecting orifices 32 positioned to project a sheet of ink against the design cylinder. In the illustrated arrangement this inking mechanism is arranged on the same side of the cylinder as the doctor 20 blade, and the sheet of ink is projected against the design as it rotates forwardly out of the body of ink in the trough 12, the sheet of ink impinging angularly on the cylinder oppositely to its direction of rotation. A suitable valve 25 32 or other control mechanism for the ink supply may be provided.

In the embodied form of the circulating system, a structure comprising vertical walls 35 and 36 extends across between, abuts against and 30 is supported by the side frames 2 of the press. Beneath the ink trough 12 and supported on the walls 35 and 36 is a horizontally-disposed foraminate plate 37, which acts as an ink strainer, the ink flowing therethrough into the chamber 38. 35 The chamber 38 is formed by the bottom parts of the vertically-disposed plates 35 and 36 together with a bottom plate 39 preferably integral with the side plates. The bottom plate 39 is preferably horizontally inclined cross-wise of the 40 press so as to provide one or more low collecting points or sumps for the ink, the ink passing thence into a return pipe 41, and is then forced back into the system by suitable means such as a pump 42 which returns the ink to the pipe 31. 45 The ink flow may be varied and controlled by a variable speed drive for the pump, if desired. A suitable splash plate 44 is mounted on the top of the side wall 35 and serves as a partial closure on that side of the design cylinder.

50 The doctor blade mechanism may be of any suitable form, so far as concerns the main features of the present invention, and as shown herein a doctor blade mechanism 45 is provided which is the same or similar to that shown, described and claimed in my co-pending application, S. N. 57,683 filed January 6, 1936.

By my present invention a very efficient and complete inking of the design is effected, through the cylinder being immersed and rotating in a body of ink, such immersion being nicely regulated as to the depth or quantity of ink so applied, while at the same time the beneficial action of an impactive stream of ink directed against the freshly inked design surface is realized, whereby a very thorough cleaning of the design is effected while at the same time an adequate supply of ink remains upon the design, as concurrently the benefits are secured of immersing application of ink to the rotating design cylinder, and a continuous and fresh circulation of the entire ink body with continuous straining and clarification of the ink is effected.

The invention in its broader aspects is not limited to the specific mechanisms shown and described but departures may be made therefrom

within the scope of the accompanying claims without departing from the principles of the invention and without sacrificing its chief advantages.

What I claim is:

1. A rotary intaglio press including in combination printing means including a design cylinder, an ink supply duct forming a pivotal mounting at one side edge of the trough, and means for moving the trough about its pivotal mounting. 10

2. A rotary intaglio press including in combination printing means including a design cylinder, a pivotal mounting at one side edge of the trough, ink supply means coaxial with the pivotal mounting, a spillway along the other side 15 edge of the trough, and means for moving the trough about its pivotal mounting to vary the immersion of the cylinder in the ink.

3. A rotary intaglio press including in combination printing means including a design cylinder, a pivotal mounting at one side edge of the trough and a spillway along the other side edge of the trough, ink supplying means, means for causing a flow of ink peripherally about the cylinder, and means for moving the trough about 20 its pivotal mounting from one to another of a plurality of levels to vary the immersion of the cylinder in the ink.

4. A rotary intaglio press including in combination printing means including a design cylinder, an ink trough for the design cylinder, means for creating ink flowage in a current peripherally of the cylinder, the ink spilling along one side edge of the trough, and means for varying the spillage level of the trough. 30

5. A rotary intaglio press including in combination printing means including a design cylinder, a ink trough for the design cylinder, means for supplying a sheet-like stream of ink from a side edge of the trough toward and about the 40 design cylinder, means for spilling a sheet-like stream of ink over the opposite side edge of the trough, and means for varying the level of the spillway edge to regulate the immersion of the design cylinder in the ink. 45

6. A rotary intaglio press including in combination printing means including a design cylinder, an ink reservoir chamber, a parti-cylindrical ink trough about the lower part of the design cylinder, means for taking ink from the 50 reservoir and projecting it in a sheet like stream from a side edge of the trough against and throughout the length of the design cylinder, the ink spilling over the opposite side edge of the trough and returning to the reservoir. 55

7. A rotary intaglio press including in combination printing means including a design cylinder, an ink reservoir chamber and a casing thereabove enclosing the greater part of the design cylinder, a parti-cylindrical ink trough within 60 the casing and positioned about the lower part of the design cylinder, means for taking ink from the reservoir and projecting it in a sheet like stream from a side edge of the trough against and throughout the length of the design cylinder, the ink spilling over the opposite side edge 65 of the trough and returning to the reservoir.

8. A rotary intaglio press including in combination printing means including a design cylinder, a spaced apart, partly cylindrical ink trough about the lower part of the design cylinder, means for projecting a stream of ink against the design, and substantially filling the space between the design and trough with a circulating 70 75

- ink flow, and means for varying the level of the ink in the trough.
9. A rotary intaglio press including in combination printing means including a design cylinder, an ink trough for the design cylinder, means for projecting a stream of ink against the design, and for filling the space between the design and trough with a circulating ink flow, and means for securing the trough at different positions so as to accommodate design cylinders of different sizes.
10. A rotary intaglio press including in combination printing means including a design cylinder, an ink trough for the design cylinder, means for projecting a sheet-like stream of ink substantially across the design, and means for variably positioning the trough to maintain a substantially uniform spacing with respect to cylinders of different diameters.
11. A rotary intaglio press including in combination printing means including a design cylinder, a pivotally mounted ink trough about the lower part of the design cylinder, means for supplying a stream of ink between the cylinder and
- trough, and means for moving the trough about its pivotal mounting to vary the level of the ink in the trough.
12. A rotary intaglio press including in combination printing means including a design cylinder, a pivotally mounted ink trough about the lower part of the design cylinder, means for projecting a stream of ink between the trough and cylinder oppositely to the rotation of the cylinder, and means for moving the trough about its pivotal mounting to regulate the level of the ink in the trough.
13. A rotary intaglio press including in combination printing means including a design cylinder, an ink trough about the lower part of the design cylinder, means for creating ink flowage between the trough and cylinder, and transversely of the trough and substantially filling the space between the design and trough, and means for varying the position of the trough to maintain a free space between the trough and design cylinders of different sizes.
